J. H. SUTTON

CHIMNEY STOP

Filed April 15, 1925

Fig. 3.

UNITED STATES PATENT OFFICE.

JOHN HARDY SUTTON, OF LA GRANGE, NORTH CAROLINA.

CHIMNEY STOP.

Application filed April 15, 1925. Serial No. 23,309.

My invention is a chimney stop or cover plate for the opening of a fire-place, and it consists in the combinations, constructions and arrangements herein described and claimed.

An object of the invention is the provision of a cover for a fire-place opening which has facilities for securing the cover firmly although releasably to the front face of the chimney wall which surrounds the fire-place opening so that the cover will be in substantially air-tight contact with the wall of the chimney and with the floor or hearth at the front of the fire-place opening and the passage of dust, cold air and the like through the fire-place opening from the chimney into the adjacent room will be prevented.

A further object of the invention is the provision of a cover of the character described which will enhance the appearance of the fire-place rather than detract from the appearance of the latter.

A still further object of the invention is the provision in a device of the character described of a novel and highly efficient means for detachably securing the fire-place cover in a desirable position with respect to the fire-place opening.

Other objects and advantages of the invention will be apparent from the following description, considered in conjunction with the accompanying drawings, in which:—

Figure 1 is a perspective view showing the improved cover applied to a fire-place,

Figure 2 is a vertical section through the cover and through a portion of the fire-place, and

Figure 3 is a fragmentary perspective view showing one of the adjustable fastening members for securing the cover in place against the fire-place structure.

The improved cover is formed of a single sheet of material, preferably a light gauge metal, and comprises a body portion 1 having an integral flange portion 2 at its upper end and integral flange portions 3 at its opposite sides, these flanges 2 and 3 extending rearwardly and outwardly from their juncture with the body 1 and being formed with outturned lip portions 2^a and 3^a, respectively, at their outer edges. The outturned lip portions 2^a and 3^a lie in the same vertical plane and are substantially parallel

to the body portion 1. The side flanges 3 also are formed with integral outturned lip portions 3^b at their bottom edges, these bottom lip portions 3^b being merged at their inner ends into a forwardly turned lip 4 which is integral with the body 1 at the lower edge of the latter. The lip portions 3^b and 4 lie in a plane which extends substantially at right angles to the body portion 1 of the cover and therefore are adapted to rest flatwise on a hearth 5 or like horizontal surface when the body portion 1 is substantially perpendicular to the hearth or like surface and the lip portions 2^a and 3^a are disposed flatwise against the front face of the fire-place structure or chimney 6 with the lip 2^a positioned above and adjacent to the plane of the upper wall of the fire-place opening 7 and the respective side lip portions 3^a being in contact with the face of the fire-place structure at opposite sides 75 of the fire-place opening. The lips at the marginal edges of the cover may be bent slightly as required to conform to irregularities of surface of the fire-place structure or hearth and it therefore will be manifest that the cover will provide a substantially air-tight seal for the fire-place opening when the cover is secured tightly to the fire-place structure in a manner which will now be described. The invention contemplates the provision of adjustable securing members as indicated at 8 for connecting the cover to the fire-place structure. Each member 8 comprises two bars 9 and 10, respectively, having the adjacent end portions thereof lapped and in sliding contact with one another, one of the bars 9 and 10 having a longitudinal slot as indicated at 11 in the bar 9 and the other bar carrying a fastening device, such as the bolt 12 which is slidable in the slot 11 and is engaged by a nut 13 whereby the bars 9 and 10 can be clamped together in adjusted position and the effective length of the member 8 thus adjusted within limits. The bar 10 is 100 twisted adjacent to its inner end and has an inner end portion 14 formed with a horizontal opening 15 adapted to fit over the free end of a horizontal anchoring stud 16 which is fixed in a side wall of the fire-place cavity and which extends for part of its length horizontally in the fire-place cavity, the free end of the stud being turned upward as in-

dicated at 17. The bars 9 of each member 8 is turned downwardly and slightly rearwardly adjacent to its outer end as indicated at 18 to rest flatwise against the inner face 5 of the body portion 1 of the cover when the member 8 is inclined upwardly toward its outer end as shown in Figure 2 and an opening 19 in the end portion 18 of the bar 9 is in register with an opening 20 in the 10 body portion 1. The outer end portion 18 of the bar 9 has a nut 21 secured permanently, as by welding, to the inner face of the portion 18 of the bar 9 in register with the opening 19 and a knob-like handle 22 15 has a threaded shank 23 adapted to be projected through the alined openings 20—19 and engaged with the nut 21. It is preferred that two of the members 8 shall be provided, one at each side of the fire-place and 20 opening, and it is manifest that manipulation of the handles 22 to thread the shanks 23 through the nuts 21 will cause the cover 1 to be clamped securely in place against the fire-place structure and on the hearth 25 5, the tightening of the handles 22 tending to draw the cover inwardly and downwardly with respect to the fire-place opening.

The handles 22 may be made of brass or any other suitable material which is susceptible of ornamentation. The cover may be embossed, painted or otherwise formed or finished to have any desirable and ornamental appearance. A strip 24 of asbestos preferably is secured by adhesive or in any 30 suitable known manner to the contact faces of the lips at the marginal edges of the cover although this sealing strip may be dispensed with if desired.

If desired, the body of the cover may be 40 provided with an opening for the reception of a stove pipe or for the reception of any suitable fitting for attachment to a stove. It of course will be understood that such opening would normally be closed by a 45 suitable lid when not employed to accommodate a stove pipe or like fitting.

It will be observed that the stop is so cupped or formed because of its construction that it is adapted to fit over a grate frame in a fire place opening even though the grate frame bulges out at the top, as is usual.

When the stop has an opening with which a pipe from a stove is attached, the entire 50 draft of the chimney will be through the stove, thus making it possible to burn any kind of fuel without clogging of the stove pipe.

The stop may be made with a marginal strengthening border or rib around the bottom if desired.

Obviously, my invention is susceptible of embodiment in forms other than that herein described and I therefore consider as my own all such modifications and adaptations 65 of the form of the device herein described as fairly fall within the scope of the appended claims.

I claim:

1. A cover of the character described comprising a plate-like body adapted to be disposed at the front of a fire-place opening in position to cover said opening, said body having an opening formed in the upper portion thereof, a fastening member comprising a pair of bar-like sections having the adjacent ends thereof adjustably connected, the outer of said bar-like sections having a downwardly and rearwardly turned end portion formed with an aperture in alignment with the opening in the body of the cover, a nut carried by said downwardly and inwardly turned end portion, and a handle positioned at the front of the cover and having a shank extended through said alined openings, and in threaded engagement with said nut, and a stud projection fast in a wall of said fire-place opening, the inner bar section of said fastening member being attached to said stud projection. 85

2. A cover of the character described comprising a plate-like body adapted to be disposed at the front of a fire-place opening in position to cover said opening, said body having an opening formed in the upper portion thereof, a fastening member comprising a pair of bar-like sections having the adjacent ends thereof adjustably connected, the outer of said bar-like sections having a downwardly and rearwardly turned end portion formed with an aperture in alignment with the opening in the body of the cover, a nut carried by said downwardly and inwardly turned end portion, and a handle positioned at the front of the cover and having a shank extended through said alined openings, and in threaded engagement with said nut, and a stud projection fast in a wall of said fire-place opening, the inner bar section of said fastening member being attached to said stud projection, said fastening member being inclined downwardly and inwardly from its outer end whereby tightening of said handle will tend to move said cover inwardly and downwardly. 105

JOHN HARDY SUTTON.
